UNITED STATES PATENT OFFICE.

JEFFERSON M. PRATT AND JOHN B. POLLY, OF ELKTON, COLORADO.

LANTERN ATTACHMENT FOR DINNER-PAILS.

SPECIFICATION forming part of Letters Patent No. 710,888, dated October 7, 1902.

Application filed December 28, 1901. Serial No. 87,619. (No model.)

To all whom it may concern:

Be it known that we, JEFFERSON M. PRATT and JOHN B. POLLY, citizens of the United States, residing at Elkton, in the county of 5 Teller and State of Colorado, have invented new and useful Improvements in Lantern Attachments for Dinner-Pails, of which the following is a specification.

This invention relates to a lantern attachment for dinner-pails; and the objects of the same are to provide a simple and effective attachment of the class set forth capable of ready application to and detachment from a dinner-pail and serving as an illuminating 10 means particularly adapted for use by miners or artisans compelled to enter or travel through dark places and also during early morning hours before light and to combine in one organization the two devices necessary 15 from a standpoint of convenience to an artisan or miner without detracting in the least from the function of either individual device; also to construct a lantern attachment in such manner that an ordinary lamp-chimney may be employed as the globe or inclosure for the flame and to have part of the body of the attachment not only serve as a 20 shield, but as means for resiliently holding the globe in positive applied position, so that 25 it can be readily detached from or secured to said body.

With these and other objects and advantages in view the invention consists in the construction and arrangement of the several 30 parts, which will be more fully hereinafter described and claimed.

In the drawings, Figure 1 is a perspective view of a dinner-pail, showing the improved lamp attachment applied thereto. Fig. 2 is 35 a detail perspective view of the lamp attachment. Fig. 3 is a transverse vertical section of the lamp attachment. Fig. 4 is a horizontal section of the lamp attachment, taken in the plane of the line 4-4 of Fig. 3.

Similar numerals of reference are employed 40 to indicate corresponding parts of the several views.

The numeral 1 designates a dinner-pail of any preferred form of construction and having, as usual, upper ears 2 for movable attachment of the bail 3. In the use of the 45 improved attachment the structure of the

dinner-pail is not in the least modified, advantage being taken of the projection of the ears 2 to effect a positive application of the 55 improved device; but it is desired that a dinner-pail be used having the ears thereof projected some distance above their points of attachment to the body of the pail.

The attachment comprises a body 4, with 60 a circular or other bottom 5, the body 4 being open at one side at its outer portion throughout the full vertical extent thereof and gradually flares from the bottom upwardly to an intermediate point, as at 6, and 65 from said point converges toward the upper extremity. The upper end of the body on opposite sides of the opening therein is formed with resilient projections 7, and, in fact, the 70 whole upper portion of the body is free to yield, the projections 7 serving as locking means and being normally spaced apart in a transverse direction a distance slightly less than the diameter of a globe or chimney 8, which is inserted between the said projections and held by the body. The opening 75 in the body 4 below the projections 7 is of such transverse extent as to permit the globe or chimney 8 to be readily inserted in the body and withdrawn from the latter, 80 and the bottom 5 has an upstanding surrounding rim 9, particularly in advance of the opening in the body, so as to engage the lower edge of the rim of the globe or chimney and 85 conjointly with the projections 7 hold the latter in immovable relation to the body until manually disengaged. The bottom 5 is supplied with a suitable burner or means for holding an illuminating device, which may be either an oil-burner, or, as shown, a socket 90 10 is provided for the reception of a candle 11, this being the simplest form of illuminating means, though it is obvious that an oil-burner may be substituted without in the least departing from the principle involved. 95 In applying the globe or chimney 8 to the body 4 the lower rim of said globe or chimney at the outer portion is caused to become positioned inside of the rim 9 and the bottom 5 by tilting or disposing the globe or chimney at an outward angle of inclination, and after the rim of the globe or chimney is so arranged the latter is pressed into the body and 100 between the projections 7, which give way or

separate, and when said globe or chimney is fully in engagement with the body the projections return to normal position, and thus securely fasten or hold the globe or chimney 5 against accidental disengagement.

The improved lantern attachment is capable of independent use, and for this purpose the upper opposite portions of the body 4 are supplied with ears 12, to which an elongated 10 bail 13 is movably attached and adapted for use in transporting the lantern in an obvious manner. The body 4 at the upper inner portion thereof has a loop 14 secured thereto and disposed transversely in a horizontal 15 plane to removably engage either one of the ears 2 of the dinner-pail 1, the said loop having an opening or throat 15 for the passage therethrough of the bail 3, engaging the said ears 2, and whereby the attachment may be 20 readily applied to and removed from either one of the ears of the dinner-pail. Below the loop 2 the body is also provided with an inwardly-extending horizontally-disposed rest 16, having opposite projecting arms 17, with 25 inwardly bent or extending angular terminals 18 to contact with the body 1 of the dinner-pail, an opening being formed between the terminals 18 to compensate for the convex surface of the body 1 and permit the said terminals to 30 firmly bear against or contact with the said body 1.

It will be seen that the rest 16 serves to maintain the attachment in positive applied position and prevents inward movement of 35 the body 4 or of the entire attachment, and the loop 14 is elongated and shaped in such manner that when it is applied over the ear 2 of the pail lateral swaying movement of the attachment will be obviated.

40 It is proposed to highly polish or otherwise prepare the inner surface of the body 4 of the attachment to produce a reflector, and it is preferred that said body and its bottom be formed of suitable metal, which may be plated 45 or otherwise ornamented.

It will be seen that the body 4 of the lantern attachment is constructed to adapt the same to receive the ordinary globe or lamp-chimney, to reduce the expense of manufacture 50 to a minimum, and also to make it possible for replacement of a broken globe or chimney by a new one at any time found necessary. This utilization of a well-known article in combination with the specially-prepared portion of the lantern attachment is 55 essentially important and a material advan-

tage in view of the fact that no special form of globe or chimney is required. It will also be apparent that the pail can be carried in such manner that the lantern attachment will 60 be projected at the front, and a convenient illuminating means will thus be provided for the use of those who are compelled to travel or move in dark places or over very dangerous and dark roads. 65

Though the preferred and simplified form of the attachment has been shown and described, it will be understood that changes in the form, proportions, dimensions, and minor details may be resorted to without departing 70 from the principle of the invention.

Having thus described our invention, what is claimed as new is—

1. A lantern attachment comprising a body having a closed bottom and an open top, and 75 a vertical opening extending from the bottom to the top, the upper portion of the body being contracted and the terminals formed by said vertical opening having a resilient operation. 80

2. A lantern attachment comprising a body which gradually diverges from a lower closed bottom to an intermediate point, and from the latter converges toward its upper end and provided with means to attach it to and support it against a dinner-pail and also formed with an open top and a vertical slot extending from the said bottom to the said open top thereof, the portion of the closed bottom which is exposed by the slot having a surrounding rim and the upper terminals formed by the slot being yieldable, whereby a lamp-chimney may be removably inserted in and held by the said body, and a bail attached to the upper portion of the body. 90 95

3. In a lantern attachment of the class set forth, a body with a lower closed base, the body being gradually reduced toward an upper open end and also having a vertical slot extending therethrough from the bottom to 100 said upper reduced end, terminals being formed by said slot which are resilient and slightly flared, and means for carrying the attachment and also supporting it in relation to a dinner-pail or the like. 105

In testimony whereof we affix our signatures in presence of two witnesses.

JEFFERSON M. PRATT.
JOHN B. POLLY.
